CLAIM

The ornamental design for a battery element as shown and described.

DESCRIPTION

1. Battery element
  2. Battery element
  3. Battery element
  4. Battery element
  5. Battery element
  6. Battery element
  7. Battery element
  8. Battery element
- 1.1** : Perspective
1.2 : Front
1.3 : Back
1.4 : Left
1.5 : Right
1.6 : Top
1.7 : Bottom
2.1 : Perspective
2.2 : Front
2.3 : Back
2.4 : Left
2.5 : Right
2.6 : Top
2.7 : Bottom
3.1 : Perspective
3.2 : Front
3.3 : Back
3.4 : Left
3.5 : Right
3.6 : Top
3.7 : Bottom
3.8 : Enlarged
4.1 : Perspective
4.2 : Front
4.3 : Back
4.4 : Left
4.5 : Right

(Continued)

4.6 : Top
4.7 : Bottom
4.8 : Enlarged
5.1 : Perspective
5.2 : Perspective
5.3 : Front
5.4 : Back
5.5 : Left
5.6 : Right
5.7 : Top
5.8 : Bottom
5.9 : Enlarged
6.1 : Perspective
6.2 : Perspective
6.3 : Front
6.4 : Back
6.5 : Left
6.6 : Right
6.7 : Top
6.8 : Bottom
